UNITED STATES PATENT OFFICE

WILHELM HAHNENKAMM AND WALDEMAR BERGER, OF FRANKFORT-ON-THE-MAIN-HOCHST, GERMANY, ASSIGNORS TO I. G. FARBENINDUSTRIE AKTINGESELLSCHAFT, OF FRANKFORT-ON-THE-MAIN, GERMANY, A CORPORATION OF GERMANY

SUPPORTING STRUCTURE FOR ROLLERS

Application filed June 27, 1928, Serial No. 288,647, and in Germany June 30, 1927.

The present invention relates to improvements in drying apparatus.

For drying industrially on a large scale substances in the form of a paste, it is advantageous to use the so-called Huillard apparatus.

Such an apparatus comprises a brick heating-chamber through which hot air is blown by means of a fan. In this chamber a band of wire netting of considerable length travels over rollers. The wire net is similar to fencing nets, except that its meshes have a width of about 10 mm. When such a narrow-meshed net is drawn through the paste, the meshes become filled with the paste which can then be dried in this state by the current of hot air. All that has then to be done to remove the dried paste is to bend the net more or less sharply over rollers of small diameter so that the dried material drops in pieces from the net. The apparatus gives very satisfactory results; its efficiency is high, and the consumption of heat is favourable because the air current passes through the apparatus in a long path on the counter-current principle. The only drawback to the apparatus in question is the excessive wear and tear of the expensive netting.

However carefully the rollers are mounted and notwithstanding the use of various auxiliary devices, such as guard rails, grooves on the rollers or pressure rollers, for the purpose of keeping the band in constant position, displacement of the band laterally is bound to occur and if this happens suddenly the net is exposed to great tension and stretched so that it is still further displaced laterally, until it becomes bent at the edge and therefore useless.

By our present invention in drying apparatus of this kind the rollers carrying the band of wire netting or other material are mounted in such a manner that they are kept in balance by a system of springs operating in the direction of the traction of the band and in axial direction of the roller. Thus the bearings may be mounted to slide, under action of the springs in planes at right angles to each other. Normally, the roller loaded with the heavy netting is kept in balance by

the bearing springs. The slightest strain or release of the netting causes the roller to yield, whereby stretching of the netting at its edges is prevented. The invention is applicable whether the net travels in vertical or horizontal planes.

A Huillard apparatus to which our invention is applied, is illustrated in the accompanying drawings, Fig. 1 being a diagrammatic vertical section and Fig. 2 a sectional view along line 2—2.

a is the brick heating-chamber through which the fan *b*, in front of a heating chamber *c*, blows hot air. *d* are baffles whose function is to cause the air to take a serpentine course through the apparatus. *e* and *e*₁ are the upper and lower guide rollers of which, for instance, the upper rollers *e* are mounted in sliding bearings and are kept in balance by springs *f* and *f*₁ in the direction of the traction of the band, and by lateral springs *g* (see Fig. 2) in the axial direction of the rollers, so that they can move in either direction when the load of the band varies. *h* is the band of wire netting. *i* is a trough which contains the paste to be dried and through which the net runs. *k* is a scraper which removes the excess of the paste. Rollers *l* serve to bend the net for removing the dried substance, which is collected in the barrel *m*. *n* is the outlet for the moisture laden air.

We claim:

In a drying apparatus comprising an endless band of wire netting travelling over a number of guide rollers, devices to maintain the balance of the guide rollers and of the band consisting of springs operative in the direction of the traction of the band, and springs operative in axial direction of the rollers, said springs being combined with each roller in its bearings.

In testimony whereof, we affix our signatures.

DR. WILHELM HAHNENKAMM. 95
WALDEMAR BERGER.
